The Spec. of

8447X

H. Blair.
Seed Planter.

Patented Oct 14, 1834.

Oct-14, 1834

259

The Schedule referred to in these letters patent, and, marking
part of the same, containing a description in the words of, the said
Henry Blair, himself, of his improvement, being a new and
useful machine for planting corn, called, the corn planter.

To all to whom these presents shall come:

Be it known, that I, Henry Blair of Glenelop in the county of
Montgomery, and state of Maryland, have invented a new and
useful improvement, in the machine for planting corn called
the corn planter, and that the following is a full and exact de-
scription of the construction and operation of the same, as invented
or improved by me. -

The frame of the machine is made as follows: ~~say~~ ^{four} ~~feet~~ six inches long and
why, two cross pieces, being turned into them, one at ten inches from
the end that will make the front of the machine, and the other
at fourteen inches from the other end or back: the timber of which
this frame is made, is thereby four inches. The beam to which the
harrow is to be attached, is twenty inches in length, turned into the
front cross piece, in the middle between the two side pieces, and then
a brace piece of timber, one by two inches, which, passes through
a mortise cut into the beam. The ends of this piece are turned into
the side pieces within six inches of their ends. To this beam is
affixed a short plough, to make the furrow, the plough bar
passes through the beam midway between the front cross piece
and the piece above mentioned, and is fastened to the top with
a bolt. A iron bolt passes thro' the plough bar, made fast to the
beam with a nut and screw; and the other end has a hole through
which passes the chain bolts: the end of the beam is provided with
a disc to which is geared a wheel.

In the top of the two side pieces are secured two
iron spears fourteen inches long, four and a half inches
in diameter. They are turned into the side pieces without
any tenon.

H. B.

sixteen inches of the front), and a hole is cut through each, to receive a cylinder hereafter to be mentioned. The dropping cylinder is six inches in diameter, between the head blocks, and at each end, there is a spade of three inches in length, that is reduced to four inches diameter, which forms the bearing of the cylinder and works in the head blocks above mentioned; it then extends six inches (on each side) out of side of the head blocks, and is there permanently attached to wheels of two feet six inches diameter. There are holes cut in the cylinder on its periphery sufficiently large to hold two, three or four grains of corn; these holes may be of any number; as the number of the holes, and the diameter of the wheels will regulate the distance at which the corn will be dropped. A box or hopper is constructed immediately above the cylinder, and extends the whole length of the cylinder between the head blocks. This box or hopper can be made to hold two or three gallons. The front part of this hopper, that is, the side towards which the cylinder revolved, is provided with a bar of iron extending the whole length of the hopper, one inch wide, and a quarter of an inch thick, riveted to an edge from the top: the lower surface of this iron bar rests on the cylinder, to prevent the grains of corn from crowding in between the cylinder and the edge of the box or hopper.

There are two wooden braces which are made fast to the front and back of the hopper, by means of iron bolts that extend from one head block to the other and are provided with a screw, at each end, so arranged as that when either the surface of the cylinder, or the edge of the hopper wears out, by turning the braces the edge of the hopper can be made to rest on the surface of the cylinder. Between this cylinder and the back edge, placed with it attached by means of a iron bolt, to the inside of the two side braces, are provided, made right and left, pads of iron, the each with one edge. Eight inches behind the head, these pads are wooden, and having the ends working loose in the two side pieces. To this, wooden, are attached

a harrow) made of two pieces of wood put together in a triangle, having its said open end to apex attached to the bar just mentioned. The teeth which are inserted into this harrow are nine, sixteen long; at the apex of the triangle and increase in length until they reach eleven inches at the base of the triangle. The back part of this harrow will be at liberty to play up and down, having its front part attached to the revolving bar. The handles are four feet long, having their lower ends let into the lower part of the head block and their upper ends elevated to two feet seven inches above the frame; they are placed in the usual manner.

Operation. When the fence draws the machine, the short plough makes a furrow to receive the grain; the cylinder is revolved with the wheels, to which it is permanently attached, catches the grain in the holes (which are made in its periphery) as they pass through to the hopper, and lets them drop into the furrow; the covers then throw the earth instead ridge over the grain; the harrow, passing over it, levels the earth and carries the large clods and stones away. The proportions herein stated, may be varied at pleasure.

That I claim as new and as my invention and for which I ask a Letters Patent, in the general arrangement and combination of the several parts. See a further illustration of my invention, referred to the model and drawing which accompany this.

In testimony that the above is a full and exact description of the construction and operation of my machine as invented and improved by me, I have caused to subscribe my hand this first day of September in the year of our Lord one thousand eight hundred & thirty four.
